(57) **CLAIM**

The ornamental design for a display screen with an animated graphical user interface for a vehicle, as shown and described.

DESCRIPTION

The patent or application file contains at least one drawing executed in color. Copies of this patent or patent application publication with color drawing(s) will be provided by the Office upon request and payment of the necessary fee.

FIG. 1 is a first image in a sequence of a display screen with an animated graphical user interface for a vehicle.

FIG. 2 is a second image in a sequence of a display screen with an animated graphical user interface for a vehicle; and, FIG. 3 is a third image in a sequence of a display screen with an animated graphical user interface for a vehicle.

The subject matter of this patent or patent application includes a process or period in which an image changes into another image. This process or period forms no part of the claimed design.

The outer dash-dash broken lines show a display screen and form no part of the claimed design. The interior dot-dash broken lines show a boundary and form no part of the claimed design. The grayscale area between the outer dash-dash broken lines and the interior dot-dash broken lines form no part of the claimed design.
